UNITED STATES PATENT OFFICE.

JOHN H. DEPELER, OF WEEHAWKEN, NEW JERSEY, ASSIGNOR TO METAL & THERMIT CORPORATION, OF CARTERET, NEW JERSEY, A CORPORATION OF NEW JERSEY.

APPARATUS FOR WELDING RAILS UNDER TRAFFIC.

Application filed February 16, 1926. Serial No. 88,644.

The invention relates to means for forming welded rail joints under traffic by the aluminothermic or similar procedure and has for its object the provision of special means for supporting the sections of the mold box in proper relation to embrace the ends of the rails to be joined and also to hold the rail ends accurately in alignment, under traffic, after the mold has been placed in position; the apparatus preferably being associated with a jumper, or double inclined ramp, which engages the tread of the rails, spanning the joint between the ends, and with means for securing the jumper to the mold box, or to the element securing the same to the rails, as will be more particularly pointed out in the following specification, based upon the accompanying drawings, in which:—

Fig. 1 is a plan view of the apparatus as applied to the rails of a standard street railway.

Fig. 2 is a side elevation of the same.

Fig. 3 is a transverse section on the line 3—3 of Fig. 1.

Fig. 4 is a perspective view of the jumper.

Fig. 5 is a perspective view of one of the yokes for securing a mold box section to the rail ends.

Fig. 6 is an end view of the installation showing the aluminothermic crucible in position.

Fig. 7 is a plan view of a modified form of apparatus.

Fig. 8 is a transverse section on the line 8—8 of Fig. 7.

Referring to Figs. 1 to 6 of the drawings, 1 and 2 indicate the half sections of a mold forming box or flask, each section comprising side and end walls and a bottom, with an open top. Each respective end wall of each mold box section is fashioned on its inner edge to conform to the contour of the lateral face and half base section of the rails A, A, to be joined, a typical configuration of the rail engaging portions of the end walls of the mold box sections as applied to a standard street railway rail being shown in Fig. 3, in which the upper edges of the mold box sections are shown as substantially flush with the tread of the rail.

Each of the mold box sections 1 and 2 is held rigidly in position in engagement with the ends of the rails to be welded by means of yokes 4 provided with lateral extensions 5, 5 having the general configuration of a fish plate or splice bar, as the case may be, and provided with bolt holes 6 to register with the bolt holes in the ends of the rails, so that each yoke is rigidly secured to the rail ends by the bolts 7 which are employed for fastening the fish plates or splice bars in place. Each yoke 4 is made somewhat larger than the mold box section which it embraces, and screw jacks 10, 10 associated with the respective yokes, serve to force the mold box sections into engagement with the opposite faces of the rails and to hold the two sections of the mold box in properly adjusted relation and prevent any displacement thereof when the wheels of traffic pass over the joint in process of formation of the latter. Each of the yokes and its associated lateral extensions, therefore, in effect, constitutes a fish plate or splice bar, which not only serves to lock together the adjacent ends of the rails to be welded and prevent any relative movement of these rail ends, but also serves to hold its associated mold box section in proper adjustment.

The molding sand, clay, or other mold forming medium, may be applied to the respective mold box sections after the latter have been clamped in position about the ends of the rail, in which case a core of wax, or similar material which defines the mold cavity surrounding the rail joint, must be applied and worked to proper form, which may be readily effected by reason of the accessibility of the interior of the mold box sections through the top or through lateral openings in the mold box sections. Alternatively the molding material may be performed before the box sections are applied to the rails by employing a suitable core having the configuration of the rail ends and the mold cavity defining projections, as will be understood. In either case, the pouring gate, riser and preheating gate are formed in the molding material by appropriate cores in usual manner.

- As thus constituted and applied, the apparatus may be employed in welding the ends of rails together by the alumino-thermic or similar method without interfering with the regular traffic, as the vehicle wheels will pass over the rail joint without interfering with or deranging the mold and without forcing the adjacent ends of the rails out of alignment, by reason of the rigid connection of the rail ends by the yokes 4, 4 and their lateral extensions, which mutually cooperate to secure the ends of the rails together with the same rigidity as the fish plates or splice bars which the yokes have replaced.
- In order to facilitate the pouring of the alumino-thermic charge, the yoke 4 connected to the outside of the rail is provided with a bracket 11 having a vertical socket 12 to receive a standard 13, which supports an arm 14 having a ring seat 15 on its outer end, in which a standard crucible 16 containing the alumino-thermic mixture is supported in vertical alignment with the pouring gate of the mold, so that, when the alumino-thermic reaction has been initiated and the steel to form the joint has been superheated and brought to a degree of high-fluidity and the crucible is tapped by knocking out the pin 17 in the bottom thereof, the highly fluid steel will be delivered into the mold. It will be noted that the crucible may be swung laterally away from the rail to permit the passage of vehicular traffic, should the contingency arise during the operations of setting up the apparatus and effecting the casting of the joint.
- As soon as the joint has been completed, the apparatus may be quickly removed for installation to form the next joint.
- Under certain conditions, it may be found advisable to relieve the ends of the rails to be joined by the welding operation, as well as the mold, from the heavy stresses imposed by passing traffic, and, to effect this object, a suitable jumper may be associated with the mold and its supporting yoke, such, for example, as the ramp-like element 20 shown in Fig. 4, provided with oppositely inclined tread sections 21, which engage the tread of the rails and extend for a considerable distance on either side of the break or joint between the rail ends. This jumper is provided with lateral lugs 23 having bifurcated ends 24, which are adapted to engage bracket-like extensions 30 on the upper edges of the yoke 4, said brackets having tap holes 31 to receive bolts 32, by means of which the jumper is rigidly locked to the yoke. To further assist in maintaining the jumper in proper position, it is formed with lateral tongues 22 fashioned to engage the groove in the rail. As thus constructed and applied, the jumper serves as a rigid bridge spanning the

ends of the rails and the vehicle wheels pass over it without imposing any appreciable load on the rail ends.

Instead of providing separate yokes 4 having lateral extensions 5, 5 for the purpose of securing the mold box sections in position and also holding the rail ends in accurate alignment, as shown in Figs. 1 to 6 inclusive, each of the mold box sections may be provided with integral lateral extensions 5', 5', as illustrated in Figs. 7 and 8, 75 said extensions having the general configuration of fish plates or splice bars, provided with bolt holes for securing them to the rail ends by the bolts employed to fasten the regular fish plates or splice bars in position. In this case, the mold box sections 1' and 2', with their lateral extensions 5', 5', are preferably formed of relatively heavy steel castings to supply the necessary strength, each mold box section preferably being provided with reinforcing flanges, such as 40 about its upper marginal edge, 41 about its ends and bottom, and 42 surrounding the lower portion of the lateral opening 43 in the side of the box section; 90 this opening 43 being provided to facilitate the application of the core and the ramming of the mold.

A bracket 11' is secured to the flange 40 of the mold box section on the outside of the rail, said bracket being provided with a socket 12' to receive the standard 13', upon which the crucible is supported in the manner and form illustrated in connection with the apparatus hereinbefore described. 105 When the jumper 20 is employed in connection with this form of mold, the flange 40 on the mold box section on the outside of the rail is made wide enough to form seats for the lugs 23, 23 of the jumper and is tapped with suitable holes to receive the bolts 32 by means of which the jumper is locked to the mold box section. It will be understood that, in constructing these mold box sections, the end walls will be fashioned to rather closely engage the base, web and under side of the head of each rail end, so that, when the two sections of the mold box are applied in position to embrace and surround the rail ends at all points except the upper face of the rail, including the tread and the groove containing flange, and the lateral extensions of the sections of the box are bolted to the ends of the rails, the entire installation will be rigidly locked to 115 the rails and the ends of the latter will be positively held against any relative movement.

The operations of forming the mold within the box sections and the casting of the joint, are practically the same as those described in connection with the preceding form of the apparatus, but, in this particu-

lar constructional exemplification of the invention, the necessity of separate yokes and clamping jacks is obviated, inasmuch as the two elements of the mold box and the means for securing the same to the ends of the rail constitute self-contained units.

What I claim is:

- 5 1. Means for forming welded joints between rail ends, comprising a mold receiving box to embrace the rail ends and means adapted to be secured to the rails to support the box and hold the rail ends in alignment.
- 10 2. Means for forming welded joints between rail ends, comprising a mold receiving box to embrace the rail ends having lateral extensions to be secured to the rails.
- 15 3. Means for forming welded joints between rail ends, comprising a mold receiving box to embrace the rail ends having integral extensions adapted to be secured to the rail webs.
- 20 4. Means for forming welded joints between rail ends, comprising a mold receiving box to embrace the rail ends having lateral extensions adapted to be secured to the rail webs on both sides of the rail.
- 25 5. Means for forming welded joints between rail ends, comprising a mold receiving box to embrace the rail ends having lateral extensions adapted to be secured to the rail webs by the usual fish plate or splice bar fastening means.
- 30 6. Means for forming welded joints between rail ends, comprising a mold receiving box to embrace the rail ends, and lateral extensions of said box adapted to engage with and be secured to the rail ends in substitution of the usual fish plates or splice bars.
- 35 7. Means for forming welded joints between rail ends, comprising mold receiving box sections adapted to be applied to opposite sides of the rails to enclose the rail ends, and means adapted to support the mold box sections and lock the rail ends together.
- 40 8. Means for forming welded joints between rail ends, comprising mold receiving box sections adapted to be applied to opposite sides of the rails to embrace the rail ends, each box section having lateral extensions to engage with and be secured to the rail ends in substitution of the usual fish plates or splice bars.
- 45 9. Means for forming welded joints between rail ends, comprising mold receiving box sections adapted to be applied to opposite sides of the rails to embrace the rail ends, each box section having integral lateral extensions to engage with and be secured to the rail ends in substitution of the usual fish plates or splice bars.
- 50 10. Means for forming welded joints between rail ends, comprising mold receiving box sections adapted to embrace the rail ends and having their side walls conforming to

the contour of the lateral faces and base section of the rails and having lateral extensions of the side walls of said sections adapted to engage the sides of the rails and be secured thereto by the usual fish plate or splice bar bolts.

11. Means for forming welded joints between rail ends, comprising a mold receiving box to embrace the rail ends, provided with lateral extensions having the general configuration of a splice bar and adapted to be secured to the rail ends in substitution of the usual splice bars.

12. Means for forming welded joints between rail ends, comprising mold receiving box sections adapted to be applied to opposite sides of the rails to embrace the rail ends, each box section having lateral extensions to engage with and be secured to the rail ends in substitution of the usual fish plates or splice bars, and each box section also having a lateral opening to facilitate the application of the core and the ramming of the mold.

13. Means for forming welded joints between rail ends, comprising a mold receiving box to embrace the rail ends, means adapted to be secured to the rails to support the box and hold the rail ends in alignment, and a jumper secured to the mold box and spanning the rail joint to take the load off the rails adjacent the joint.

14. Means for forming welded joints between rail ends, comprising a mold receiving box to embrace the rail ends, means adapted to be secured to the rails to support the box and hold the rail ends in alignment, and a jumper including oppositely inclined ramp sections overlying the rail treads at the joint, and means for securing the jumper to the casting installation on the outside of the rails.

15. Means for forming welded joints between rail ends, comprising a mold receiving box to embrace the rail ends, means adapted to be secured to the rails to support the box and hold the rail ends in alignment, and a jumper including oppositely inclined ramp sections overlying the rail treads at the joint, flanges engaging the rail grooves, and means for securing the jumper to the casting installation on the outside of the rails.

16. Means for forming welded joints between rail ends, comprising a mold receiving box to embrace the rail ends, means adapted to be secured to the rails to support the box and hold the rail ends in alignment, and a jumper including oppositely inclined ramp sections overlying the rail treads at the joint, and lugs on the jumper for securing the latter to the mold box on the outside of the rails.

17. Means for forming welded joints between rail ends, comprising a mold receiving

box to embrace the rail ends, and a jumper secured to the mold box and spanning the rail joint to take the load off the rails adjacent the joint.

5 18. Means for forming welded joints between rail ends, comprising a mold receiving box to embrace the rail ends, and a

jumper secured to the mold box and spanning the rail joint and mold box and including oppositely inclined ramp sections engaging the rails at either side of said joint and mold box.

In testimony whereof I affix my signature.

JOHN H. DEPPELER.
